[57] **CLAIM**

The ornamental design for a link for a bicycle chain, as shown and described.

DESCRIPTION

FIG. 1 is a top plan view of a link for a bicycle chain in accordance with my new design;

FIG. 2 is a front elevational view of the link illustrated in FIG. 1, with the back elevational view of the link being identical;

FIG. 3 is a right side elevational view of the link illustrated in FIGS. 1 and 2, with the left side elevational view of the link being identical; and,

FIG. 4 is a bottom plan view of the link illustrated in FIGS. 1-3.
